H. TRUST ET AL
MIXING AND BEATING MACHINE

Filed Jan. 9, 1920

UNITED STATES PATENT OFFICE.

HENRY TRUST, OF PARK RIDGE, NEW JERSEY, AND FRANK M. ASHLEY, OF BROOKLYN, NEW YORK; SAID ASHLEY ASSIGNEE TO JOSEPHINE TRUST, OF PARK RIDGE, NEW JERSEY; JOSEPHINE TRUST ADMINISTRATRIX OF SAID HENRY TRUST, DECEASED.

MIXING AND BEATING MACHINE.

Application filed January 9, 1920. Serial No. 350,391.

To all whom it may concern:

Be it known that we, HENRY TRUST, a citizen of the United States, and resident of Park Ridge, in the county of Bergen and State of New Jersey, and FRANK M. ASHLEY, a citizen of the United States, and resident of Brooklyn, in the county of Kings and State of New York, have invented certain new and useful Improvements in Mixing and Beating Machines, of which the following is a specification.

Our invention relates to mixing and beating machines and the object of our invention is to provide an attachment for machines of this character that can be driven by the main driving spindle and can be easily detached from the casing of the machine and comprising gearing of different specific construction to permit different speeds of the small gear wheels relative to the speed of the driving shaft, as well as different distances between the main and driven spindles to accommodate beaters of different diameters to be used in the mixing receptacles.

Further objects will be hereinafter stated and the novel features of the construction pointed out in the claims.

Referring to the drawings which form a part of this specification.

Figure 1 is a vertical sectional view of a construction embodying our invention.

Figure 2 is an inverted plan view on a reduced scale.

Figure 3 is a vertical sectional view of a construction embodying our invention, of more compact form, the gear ring and pinion of which can be inserted in the deeper casing illustrated in Figure 1.

A indicates the casing of the mixing machine and B the detachable housing which is held to the casing by stud-bolts C—C. D indicates the main driving shaft which carries a casting E held thereto by a key D'.

The inner face B' of the housing B is formed smooth and cylindrical and is open at its upper end, and a shoulder B² is formed which extends entirely around the cylinder and supports a steel or bronze gear ring F having gear teeth F' cut therein.

This gear ring is fastened securely to the cast iron housing B in such manner as to be readily removed. An annular groove B² is formed in the housing adjacent the

opening B³ in the lower end of the housing B. The casting E, hereinafter referred to as the carrier, is provided with a downwardly extending ring-like projection E' which rests in the annular groove B², the bottom of which serves as a bearing for the portion E' and also holds oil to lubricate the same. A depending hub B⁴ is provided with a bearing B⁵ in which is supported a spindle G which is driven by a gear wheel H mounted thereon and held by a set screw G'. This gear wheel H meshes with the gear teeth F'. Further spindles and gear wheels, indicated in dotted lines J, may be supported in like manner to drive two or more chucks such as I, which carry the beaters. The gear wheel H may be disengaged from the teeth F' by lifting the spindle G until the gear H is in the position indicated by dotted lines K.

Referring now to the construction illustrated in Figure 3, it will be observed that the housing L is exactly like the housing B except that it is not so deep. The carrier M is practically the same as that indicated by E, the main difference being that the central hub N, shown in Figure 1, extends upward within the housing B, whereas in Figure 3 the hub O, which serves the same purpose, extends downward and is held to the shaft D by a pin P instead of the key D'. Instead of using spur gears as illustrated in Figure 1, we provide a gear ring Q with bevel gear teeth Q', and a bevel gear wheel R is used in place of the same spur gear H. This construction permits a much more shallow housing than that used in the construction shown in Figure 1. In both cases, the gear rings F and Q project toward the centre in overlapping relation to the outer edge of the carrier which holds the parts together when the housing is removed from the casing A.

The operation is as follows:

The shaft D in its rotation drives the carrier E, causing the gear wheel H to rotate as the parts are revolved about the shaft D and thus driving the spindle G and beater carried by the chuck I, as will be readily understood.

The wearing parts are easy to duplicate or replace when worn and by using steel gears, the life of the machine is greatly increased.

Having thus described our invention, we claim as new and desire to secure by Letters Patent:

1. A machine of the character described comprising a casing, a housing connected to and depending therefrom and having an opening in its lower end, a guide flange forming a part of the said housing, a spindle supported in said casing, a carrier connected to said spindle and having a flange supported by the flange of the housing, a toothed ring rigidly connected with said housing, a gear wheel carried by said carrier and adapted to mesh with the said toothed ring.
2. A machine of the character described comprising a casing, a housing connected thereto and having an opening in its lower end, a flange forming a part of said housing, an upwardly projecting circular ridge connected with said flange, a spindle supported in said casing, a carrier rigidly connected with said spindle, a circular flange forming a part of said carrier and adapted to co-act with the circular ridge of the flange whereby the carrier is guided, a toothed ring rigidly mounted in said housing, a spindle carried by said carrier, a gear wheel rigidly mounted on said last mentioned spindle, said gear wheel being adapted to mesh with the teeth of the toothed ring.
3. A machine of the character described comprising a casing, a housing connected to and depending therefrom having an opening in its lower end and an annular groove formed adjacent thereto, a spindle supported in said casing and depending therefrom, a carrier connected to said spindle and having a depending portion located

in said annular groove in the housing, a gear ring carried by said housing, a spindle, a gear wheel mounted on said spindle and carried by said carrier, said gear wheel meshing with the gear teeth of said gear ring.

4. A machine of the character described comprising a casing, a housing connected to and depending therefrom having an opening in its lower end and an annular groove formed adjacent thereto, a spindle supported in said casing and depending therefrom, a carrier connected to said spindle and having a depending portion located in said annular groove in the housing, a gear ring carried by said housing and located above said carrier, a spindle, a gear wheel mounted on said spindle and carried by said carrier, said gear wheel meshing with the gear teeth of said gear ring.

5. A machine of the character described comprising a casing, a housing connected to and depending therefrom having an opening in its lower end and an annular groove formed adjacent thereto, a spindle supported in said casing and depending therefrom, a carrier connected to said spindle and having a depending portion located in said annular groove in the housing, a gear ring enclosed and carried by said housing, a spindle, a gear wheel mounted on said spindle and carried by said carrier, said gear wheel meshing with the gear teeth of said gear ring.

Signed at New York city, in the county of New York and State of New York, this 8th day of January, A. D. 1920.

HENRY TRUST.
FRANK M. ASHLEY.
